Attorney

UNITED STATES PATENT OFFICE.

WALTER G. VREELAND, OF CHATTANOOGA, TENNESSEE, ASSIGNOR TO LACEY MANUFACTURING CORPORATION, OF CHATTANOOGA, TENNESSEE, A CORPORATION OF TENNESSEE.

RESILIENT ATTACHMENT FOR WELL-CASINGS.

1,269,232.

Specification of Letters Patent. Patented June 11, 1918.

Application filed May 18, 1917. Serial No. 169,549.

To all whom it may concern:

Be it known that I, WALTER G. VREELAND, a citizen of the United States, residing at Chattanooga, in the county of Hamilton and 5 State of Tennessee, have invented certain new and useful Improvements in Resilient Attachments for Well-Casings, of which the following is a specification.

My invention relates to resilient attachments especially for use in connection with 10 casing rigs used in rotary well drilling.

During the progress of well drilling, as 15 the depth of the well increases, it is necessary to keep adding lengths of casing which necessitates a considerable amount of screwing and unscrewing at the connecting joints.

Great difficulties have been experienced on account of the weight of the upper members, which have to be raised to allow the insertion 20 of the additional lengths of casing, tending to bur the threads when the joint is being coupled or uncoupled.

It is an object of my invention to provide 25 an attachment which will hold the upper joints in suspension and keep the connecting members in alinement thereby eliminating the strain and wear on the threads while screwing or unscrewing the casing.

By using my device in a rotary well drilling outfit where a swivel is used, the swivel 30 will be relieved of considerable strain when the drilling member comes into sudden contact with the bottom of the well thereby adding to the wearing qualities of the 35 swivel.

It will also be found that with the use of 40 my device the derrick and hoisting machinery is relieved of a considerable strain when the slack of the cable is taken up upon the hoisting of the casing.

With the above and other objects in view which will appear as the nature of my invention is better understood, my invention consists in the novel features hereinafter 45 described, illustrated in the accompanying drawings and more particularly pointed out in the appended claims.

Referring to the drawings;

Figure 1 is a detail view of the attachment 50 showing it attached to a casing hook and swivel.

Fig. 2 is a side elevation of Fig. 1.

In the drawings 1 designates my attachment 55 which is shown connected at its top to a casing or cable hook A, said hook being

supported from the hoisting cable (not shown). The lower end of my device is shown connected to the bail of a swivel B.

The construction of my device consists of two links 2 and 3, the upper ends of which 60 are apertured to receive the trunnions 4 and 5 projecting from the crosshead. These links are held in position on the trunnions by means of the washers 7 and tap bolts 8. The crosshead 6 is provided with a 65 rectangular aperture 9 to loosely receive the stem 10, the upper end of said stem being provided with a hole 11 to receive the pintle 12. The bail 13 straddles the upper end of the stem 8 and is provided with apertures to 70 receive the projecting ends of said pintle 12. Pins 14 are provided through the pintle 12 to retain it in position.

The lower ends of the links 2 and 3 are apertured similar to the upper ends and receive the shaft 15 to which is connected the bail 16 and a spacing ring 17. The shaft 15 being held in relative position by means 75 of the pins 18.

The lower end of the stem 10 is threaded 80 to receive the nut 19 which holds in place a disk 20. The upper face of said disk is provided with a seat to which is fitted the sleeve 22, said sleeve serving as a partial housing for a compression spring 21 and as 85 a resilient support for the lower bail 16 when the full load is attached.

In using my attachment while raising a well casing, the swivel B is secured to the upper end of the line while the bail 13 is 90 connected to the cable hook A. After the upper section of the casing is above the level of the table the next section is gripped in the usual manner for the purpose of independently supporting the casing. As the 95 casing is being lifted, the spring 21 will be compressed until the sleeve 22 engages the crosshead and during the lifting the weight of the rig will be supported by said sleeve. As the upper section of the casing is unscrewed from the casing proper, the spring 21 will expand causing the crosshead 6 to move upwardly thereby relieving the threads of the casing joints from the strain incident to disconnecting the sections of the 100 casing. During the removal of the upper section of the casing, the swivel B permits the upper section to be turned while any lateral movement of the upper section and swivel will be accommodated by the pivots 105 110

12, 5 and 15. During drilling, the operation just described is reversed as will be apparent to those skilled in the art.

While I have herein shown and described 5 a specific embodiment of my invention, it is to be understood that in practice, I may resort to such modifications as fall within the scope of the invention as defined in the appended claims.

10 I claim:

1. A resilient attachment for well rigs comprising upper and lower bails for connection between two of the upper members of a well rig, links connected to said lower 15 bail and carrying a crosshead, a stem connected to the upper bail, resilient means interposed between the lower end of said stem and said crosshead adapted to carry the load supported from said lower bail and to 20 turn said lower bail to its normal position after a vertical movement thereof, and means to limit the downward movement of said lower bail and relieve the load on said resilient means when the latter has 25 contracted a predetermined amount.

2. A resilient attachment for well rigs comprising upper and lower bails for connection between two of the upper members of a well rig, links pivotally connected to 30 said lower bail and pivotally connected at their upper ends to a crosshead, a stem pivotally connected to the upper bail and passing through an aperture in said crosshead, resilient means interposed between 35 the lower end of said stem and said crosshead and adapted to carry the load supported from said lower bail and to return said lower bail to its normal position after

a vertical movement thereof, and means to limit the downward movement of said lower 40 bail and relieve the load on said resilient means when the latter has contracted a predetermined amount.

3. A resilient attachment for well rigs comprising upper and lower bails for connection between two of the upper members of a well rig, an apertured cross-head, links pivotally connected at their lower ends to said lower bail and pivotally connected at 45 their upper ends to said apertured cross-head, a stem carried by the upper bail extending through the aperture of the cross-head and provided at its lower end with a disk, and a spring interposed between said crosshead and said disk.

4. A resilient attachment for well rigs comprising upper and lower bails for connection between two of the upper members of a rig, an apertured cross-head, links pivotally connected at their lower ends to said 50 lower bail and pivotally connected to the upper ends of said apertured cross-head, a stem pivotally connected to the upper bail extending through the aperture of said cross-head and provided at its lower end with a disk, a sleeve carried by said disk, and a spring interposed between said crosshead and said disk.

In witness whereof I set my hand and affix my signature in the presence of two 70 subscribing witnesses.

WALTER G. VREELAND.
